UNITED STATES PATENT OFFICE

ALFRED F. MASURY, OF NEW YORK, N. Y., ASSIGNOR TO INTERNATIONAL MOTOR COMPANY, OF NEW YORK, N. Y., A CORPORATION OF DELAWARE

REFUSE DISPOSAL TRUCK

Application filed May 29, 1930. Serial No. 456,938.

The present invention relates to motor vehicles adapted particularly for the transportation and disposal of refuse, such as garbage, ashes, etc., and embodies more specifically, an improved vehicle by means of which the collection and disposal of the refuse is greatly facilitated.

One of the most important considerations in the design of vehicles for service of this character is that of providing a relatively low body in order that the refuse may be loaded therein readily. It is further necessary that the body be of such character that the contents may be readily transported and dumped, such characteristics being combined with those of simplicity of design and strength and efficiency in operation.

An object of the invention, accordingly, is to provide a vehicle of the above character by means of which refuse may be readily loaded therein and effectively transported and dumped.

A further object of the invention is to provide a device of the above character, the construction of which is comparatively simple and the operation of which is highly effective in service.

Further objects, not specifically enumerated above, will be apparent as the invention is described in greater detail in connection with the accompanying drawings, wherein:

Figure 1 is a view in side elevation, showing a vehicle constructed in accordance with the present invention.

Figure 2 is a detail view showing the manner of mounting the wheels upon the body of the vehicle shown in Figure 1.

Figure 3 is a detail view, partly broken away and in section, showing the manner of mounting the trailer body upon the tractor in the construction of Figure 1.

Figure 4 is a view in rear elevation, showing the trailer body of Figure 1.

Figure 5 is a view in section, taken on line 5-5 of Figure 2, and looking in the direction of the arrows.

Figure 6 is a view in side elevation, partly broken away and in section, showing a modified form of the invention.

Figure 7 is a perspective view, showing the body which is mounted for dumping upon the vehicle shown in Figure 6.

Figure 8 is a view in end elevation, showing the vehicle of Figure 6.

Figure 9 is a diagrammatic view, showing

the manner in which the body of Figure 7 is dumped.

Figure 10 is a view in section, similar to Figure 5, showing a modified wheel mounting.

Figure 11 is a segmental view in side elevation, partly broken away and in section, showing the wheel mounting of Figure 10.

Referring particularly to Figures 1 and 5 of the above drawings, *a* designates a tractor which is preferably of a standard and well known design, a hoisting mechanism *a'* being provided thereon for hoisting the trailer body as described hereinafter.

A fifth wheel *a*² is provided on the tractor and mounts a plate *b* pivoted thereon. This plate is provided with downwardly projecting arms *b'*, at either side of the vehicle, the arms having hoisting cables *b*² secured to the ends thereof, as clearly shown in Figure 1.

A body *c* constituting a trailer is provided with a forwardly extending portion *c'* which is secured to the plate *b* for relative rotation therewith about the axis of the fifth wheel. A slot *b*² is preferably formed in the plate *b* and receives a pin *c*², carried by the forwardly extending portion *c'* of the body *c*, thus limiting the relative movement between the plate *b* and forwardly extending portions *c'*.

Upon the opposite sides of the body *c*, rearwardly thereof, are mounted stub shafts *d*, there being two of such shafts upon either side of the body. These shafts journal radius rods *d'*, upon the outer ends of which wheels *e* are journaled. Stub shafts *d*² are preferably provided for mounting the wheels *e* upon the arms and a spring *f* preferably transmits the weight of the body to the axles and wheels.

An intermediate stub shaft *g*, mounted between the shafts *d*, serves as an anchor tube for the spring *f*, the latter being journaled thereon intermediate its ends. Bearing pads *d*³ are formed upon the radius rods *d'* and seat the ends of spring *f* as clearly shown in Figures 2 and 5. The stub shaft *g* preferably carries a bracket *g'* which is formed with a slot *g*² for receiving the end of the forward radius rod *d'* as clearly shown in Figure 5.

The foregoing construction provides an extremely low body for the trailer, the clearance thereof being designed in accordance with the various conditions under which the vehicle is to operate. If desired, the sides

may be provided with outwardly extending flaring portions c^3 to facilitate loading of the vehicle, the rear of the body being formed with a sloping end c^4 to facilitate the dumping operation.

- In the construction shown in Figures 6, 7, 8, and 9, the vehicle is provided with a trailer having relatively deep side frame members i which are secured to the fifth wheel a^2 .
 10 These frame members constitute a semi-trailer body upon which the wheels e are mounted. Carried through the fifth wheel in any well known manner is a power take off shaft j which transmits power rearwardly to a dumping mechanism k carried upon the frame i . A body l is pivoted at l' upon the frame, this pivot point being relatively high in order that the body may be elevated sufficiently in dumping.
 15 20 As shown in Figure 7, the body is formed with a plurality of apertures l^2 over which sliding doors l^3 may be mounted in any well known manner.

Coaxial with the fifth wheel is a cleaner m which is secured to the tractor and thus permits turning of the forward extremity of the frame i with respect thereto. A suitable conduit m' directs the flow of air from the cleaner to the engine cooling system which 25 30 35 may be of any well known form. A conduit l^4 is secured to the body l and is movable therewith. This conduit communicates with an aperture m^2 in the cleaner m , the connection therewith preferably being a ball joint 40 to permit relative turning of the conduit with respect to the cleaner. In assuming the dumping angle, the conduit passes upwardly through a recess m^3 in the cleaner m , thus permitting the dumping of the body l without obstructing the conduit.

With reference to Figures 10 and 11, the wheel mountings are all of a modified form, stub shafts d carrying sleeves n to which distance plates n' are secured. A bracket o is secured to each stub shaft d and is provided with an arm o' to which a coil spring p is secured. After forming the desired number of coils, the outer end of the spring p is secured over the distance plate n' at p' as clearly shown in Figure 11.

Upon the rearward portion of each distance plate n' , a bracket q is secured, this bracket q being formed with a stub shaft q' and rollers q^2 which ride in a bifurcated track r . Upon the side frames i , housings s are secured, these housings carrying yielding non-metallic material s' . Rearwardly extending arms r' , formed on the bifurcated tracks r , are received in the yielding non-metallic material s' and thus cushion the lateral movement of the rear of the distance plates n' .

It will thus be seen that the body c , cradled in the frame, is effectively ventilated by the 65 conduit l^4 , the cleaner m serving to remove

foreign particles from the air. The pivoting of the body upon the frame members i being at a relatively high point, permits the effective dumping of the body without causing interference between the extreme end thereof and the ground.

From the foregoing, it will be seen that the body c is admirably adapted for service such as the collection and dumping of refuse, etc., the construction being simple and of great strength to withstand the hard usage to which such vehicles are put. In the dumping operation, the body c moves about the axis of the rear wheels, as clearly shown in dot and dash lines in Figure 1. In view of the fact that the forward of the rear wheels leave the ground during dumping, a stop lug h is formed on the forward radius rods d' to limit the movement of the wheels with respect to the body when the latter is dumped. While the invention has been described with specific reference to the accompanying drawings, it is not to be limited, save as defined in the appended claims.

I claim as my invention:

1. A vehicle construction comprising a radius rod journaled upon each side of the body, springs between the radius rods and the body, wheels journaled upon the rods, guide tracks, housings on each side of the trailer, cushioning means in the housings, means to mount the guide tracks in the cushioning means, and means on the rods engaging the guide tracks.

2. A vehicle construction comprising a radius rod journaled upon each side of the body, springs between the radius rods and the body, wheels journaled upon the rods, guide tracks, housings on each side of the trailer, cushioning means in the housings, a plurality of arms on the guide tracks mounted in the cushioning means, and means on the rods engaging the guide tracks.

3. A vehicle construction comprising a radius rod journaled upon each side of the body, springs between the radius rods and the body, wheels journaled upon the rods, arcuate guide tracks, arcuate housings on each side of the trailer, cushioning means in the housings, means to mount the guide tracks in the cushioning means, and means on the rods engaging the guide tracks.

4. A vehicle construction comprising a radius rod journaled upon each side of the vehicle, springs between the radius rods and the vehicle, wheels journaled upon the rods, guide tracks, means to mount the tracks yieldingly upon opposite sides of the vehicle independent of the rods, and means on the rods engaging the guide tracks.

This specification signed this 26th day of May A. D. 1930.

ALFRED F. MASURY.
